Primary Examiner — Ian Simmons*Assistant Examiner* — Carissa C Fitts(74) *Attorney, Agent, or Firm* — Karen G. Horowitz(57) **CLAIM**

We claim the ornamental design for a personal care device, as shown and described.

DESCRIPTION

FIG. 1 is a perspective view of the personal care device showing our new design;

FIG. 2 is a front view thereof;

FIG. 3 is a bottom view thereof;

FIG. 4 is a left side elevational view thereof, the right side elevational view being a mirror image thereof;

FIG. 5 is a top view thereof; and,

FIG. 6 is a rear view thereof.

The dot-dash broken lines immediately adjacent the shaded areas represent the bounds of the claimed design while all other broken lines are directed to the environment and are for environmental purposes only; the broken lines form no part of the claimed design.
